UNITED STATES PATENT OFFICE.

RANSOM W. DAVENPORT, OF DETROIT, MICHIGAN, ASSIGNOR TO DETROIT STOVE WORKS,
OF DETROIT, MICHIGAN, A CORPORATION OF MICHIGAN.

COMBINED COAL AND GAS RANGE.

1,265,432.

Specification of Letters Patent.

Patented May 7, 1918.

Application filed August 26, 1915. Serial No. 47,414.

To all whom it may concern:

Be it known that I, RANSOM W. DAVENPORT, a citizen of the United States of America, residing at Detroit, in the county of Wayne and State of Michigan, have invented certain new and useful Improvements in Combined Coal and Gas Ranges, of which the following is a specification, reference being had therein to the accompanying drawings.

The invention relates to stoves of that type designed for use with either solid or gaseous fuel, and the invention comprises the novel construction as hereinafter set forth.

15 In the drawing:—

Figure 1 is a longitudinal section through the combined range;

Fig. 2 is a cross section thereof on line $x-x$;

20 Fig. 3 is a horizontal section.

A is a cooking range of any suitable construction and provided with the usual fire-box B, oven C, top flue D, down flue E, bottom flue F and rear flue G. H is the 25 grate at the bottom of the fire-box, and beneath this is an ash-pit I, all of the parts being of usual construction.

It is the primary object of the invention to 30 equip a solid fuel range, such as above described, with a gas heater so arranged as to avoid any interference with the transmission of heat from the flues or the normal operation of the stove with coal. Inasmuch as the flues extend across the top and bottom, one 35 end and in rear, and as the fire-box is arranged at the other end, the oven is almost completely surrounded. There is, however, a flueless wall which is intermediate the ash-pit and one side of the oven, and I have 40 therefore located the gas burners at this point. As shown J is the delivery end portion of the gas burner which extends upward through the bottom of the range between the ash-pit and the oven, and discharges 45 through an aperture in the oven wall laterally over the oven bottom. The portion J of the burner is connected with a laterally-extending portion K, which is arranged within the base ring L, extending through 50 the end of the stove where it is provided with a gas valve M and the usual air-mixer O. P is a deflector or false bottom, which is arranged above the burner and is removable when the range is used with solid fuel. Q 55 is a damper for closing the aperture with

which the burner registers, and R is another damper for closing and opening an exit opening S near the top of the oven. The dampers Q and R are preferably connected with a common actuating mechanism, such as T, arranged outside of the stove, and by means of which said dampers may be simultaneously opened or closed.

With the construction as described, when the range is used with solid fuel, the dampers Q and R are closed and the deflector or false bottom P is removed. The products of combustion of the fuel in the fire-box will then pass around through the flues D E F G without interference from any part of the gas heating apparatus, and furthermore the arrangement of the gas burner J does not interfere with the efficiency of the stove in any way, for the reason that it is adjacent to a portion of the oven wall which is flueless. To use the range with gaseous fuel, all that is necessary is to open the dampers Q and R by the common actuating mechanism T and place the deflector or false bottom P in position. When thus 80 adjusted the flame from the burner will pass over the bottom of the oven beneath the false bottom, and the heated gases of combustion will pass upward through the oven and out through the escape flue S.

As specifically shown, the oven is provided with a pocket U in its rear wall in which the exit opening S and damper R are located. The damper R has a rotary actuating stem R' which passes to the end of the range, and is provided with a crank R² connected to a pull-rod R³. This pull-rod has a handle portion R⁴ for operating the same, and which also performs the function of a stop for preventing the turning of the handle M' of the valve M when the dampers are closed. The rod R' within the oven has a crank arm R⁵ connected by a rod R⁶ and chain or other flexible connection R⁷ with the damper Q, the arrangement being such that the actuation of the handle R⁴ will simultaneously open or close both dampers R and Q.

What I claim as my invention is:

1. In a cook stove, the combination with 105 an oven, of an ash-pit and superposed fire-box at one side thereof and flues extending from said fire-box over the top, down at one side beneath the bottom and to the rear of said oven, a gas burner having a portion 110

- arranged between said ash-pit and oven and discharging laterally through an aperture in the oven wall into the lower portion thereof, a removable deflector or false bottom arranged above the level of discharge of said burner, and co-acting dampers for respectively controlling said aperture and a discharge opening from the top of the oven and a common means actuating said dampers.
2. In a cook stove, the combination with an oven, a fire-box and flues for the products of combustion extending from said fire-box around said oven, of a gas burner arranged adjacent to a flueless portion of the oven wall and directed into said oven, dampers controlling the opening into said oven for said burner and an exit opening, a common actuating connection for said dampers by which both may be simultaneously opened or closed, a valve for the gas burner, and a stop on said actuating mechanism for preventing the opening of said valve when said dampers are closed.
3. In a cook stove, the combination with an oven, a fire-box and flues for the products of combustion extending from said fire-box around said oven, of a gas burner arranged to discharge into the oven adjacent the bottom thereof, a discharge flue in communication with said flues rising adjacent the oven at the rear thereof, and offset rearwardly to form a recess in the oven rear wall, an outlet being formed in said recess from the

oven to said flue, a damper controlling said outlet arranged in said recess.

4. In a cook stove, the combination with an oven, a fire-box and flues for the products of combustion extending from said fire-box around the oven, a gas burner adapted to discharge into the oven, dampers respectively controlling the opening into said oven for said burner and an exit opening therefrom, a common actuating connection for said dampers by which both may be simultaneously opened or closed, a valve for the gas burner, and a stop on said actuating mechanism for preventing the opening of said valve when said dampers are closed.

5. In a cook stove, the combination with an oven, of a fire-box and flues for the products of combustion extending from said fire-box around said oven, means for heating said oven by the introduction of hot gases thereinto, a discharge flue rising adjacent the oven at the rear thereof and offset rearwardly to form a recess in the oven, an outlet being formed in said recess from said oven to the flue, and a damper controlling said outlet arranged in said recess.

In testimony whereof I affix my signature in presence of two witnesses.

RANSOM W. DAVENPORT.
